(57) **CLAIM**

The ornamental design for a chair, as shown and described.

DESCRIPTION

FIG. 1 is a perspective view of the chair of my design;

FIG. 2 is a top view of the chair;

FIG. 3 is a front view of the chair;

FIG. 4 is right side facing view of the chair (the left side facing view, being a mirror image of the right side facing view, is not shown);

FIG. 5 is a back view of the chair; and,

FIG. 6 is a bottom view of the chair.

The broken lines shown in the drawings are for illustrative purposes only and form no part of the claimed design.
